HOSIERY FORM ATTACHMENT

Stanley Nettler, Great Neck, N. Y.

Application November 28, 1950, Serial No. 197,997

8 Claims. (Cl. 223—75)

1

This invention relates broadly to the hosiery form art, and in its more specific aspects it relates to an attachment for association with a form for displaying hosiery which functions to maintain the displayed hose in stretched proper position on the form and provides means for holding and displaying a price or advertising card; and the nature and objects of the invention will be readily recognized and understood by those skilled in the arts to which it relates in the light of the following explanation and detailed description of the accompanying drawings illustrating what I at present believe to be the preferred embodiments and mechanical expressions of my invention from among various other forms, arrangements, combinations and constructions, of which the invention is capable within the spirit and scope thereof.

It is conventional practice to display nylon, silk and other types of hose on plastic or the like forms shaped to simulate the human leg. Such forms may be molded or otherwise formed to stand erect on the forward position of the foot or may be maintained in upright position by a supporting frame. A hose is drawn tightly over the smooth exterior surface of the form and when the form is in erect position with a hose thereon the effect produced is that of a hose clad human leg. Hosiery forms of this general character are widely used to display hose in store windows, counters and in various other display locations.

The forms which are in general use at present are of hollow or tubular construction and are open at the upper end. Some of such forms are in simulation of that portion of the human leg from below the knee and include a foot simulating portion, while others include a knee simulating part. In the use of hosiery forms of this character, regardless of their length, the hose is pulled or drawn on the form and stretched as tightly as possible thereon so that it will closely resemble a hose when on the human leg. All of the hosiery forms now in use and with which I am familiar are of less length than the hose displayed on the form and thus there is a surplus top portion of hose remaining after it is applied on a form. It is desirable to take care of this surplus hose in some manner which will not detract from the overall ornamental and advertising effect of the display and to use this surplus hose to keep the hose stretched and tight on the form. Many modes of arranging the surplus part of the hose so that it will serve these purposes have been tried and they are all time consuming and do not maintain the hose in proper stretched condition

2

on the form, and usually require attention or adjustment. For instance, the extra or surplus portion of the hose may be merely stuffed or wadded into the upper open end of the form, or it may be twisted and tied with a rubber band forming a pompon effect, or other means of caring for this surplus part of the hose which extends beyond the upper open end of the form are used. As far as I am aware no positive anchoring means for the surplus hose has been practised in the past.

The display forms for hosiery with which I am familiar provide no means for maintaining the hose in tightly stretched condition thereon so that in present display forms puckering or loosening occurs to disturb the desired effect of a properly fitted hose on a human leg. The forms in which the hose is merely tied, stuffed or otherwise associated with the open end thereof are not entirely satisfactory as the hose will become loosened and will pucker, and if a hose with a seam is being displayed the seam may become displaced and the effectiveness of the display will be lost. Hose may be effected by atmospheric conditions and it will thus be evident that the loosening and puckering of a form displayed hose may be considerably exaggerated under certain atmospheric conditions.

Forms of the general character of those with which my attachment is adapted for use may be used in display windows or the like where access to one or more forms may be difficult and may necessitate disarrangement of all or a substantial part of the display contained in the window. It will be evident that hosiery forms of the type now in use which do not ensure maintenance of the hose in proper position thereon snugly fitting the form will require attention to properly rearrange the displayed hose. Hence, window displays must be disarranged so that a hose may be straightened and adjusted on one or more particular forms and considerable time will be consumed and lost. Constant adjustment of a displayed hose may also result in runs in the hose.

I have devised a simple and inexpensive device for association with the displayed hose and the form, which overcomes the disadvantages inherent in the hosiery forms currently in use and functions to maintain the hose in proper position and condition on the form so that it will not loosen or pucker and the desired stockinginged human leg simulation will be kept as long as the hose is on the form. In designing this attachment I have made use of the elastic nature of hosiery and have provided means for stretching a surplus part of a hose to thereby produce a taut-

ness or tensioned effect on the hose on the form.

The attachment which I have devised includes an element which receives, and in effect stores the upper or surplus part of a hose which extends beyond the open upper end of the form and the hose is fastened to the element and the element and the extra length of hose is disposed within the form through the open upper end thereof. I provide a top or housing for the hose receiving and anchoring element which forms a pleasing ornamental effect at the upper end of the hosiery form, while also functioning with the element to maintain the displayed hose in tightly stretched proper position.

The attachment which I have devised stretches the hose over the form like a drum and maintains it in this tightly stretched condition. I accomplish this highly desirable and satisfactory result by providing a unique organization which, when in operative position produces certain friction and pressures on the hose relative to the form so that the hose will be maintained in such tightly stretched condition. My device functions in this manner while producing a desirable ornamental effect at the top of the form which is considerably more pleasing than that heretofore produced by merely bunching or wadding the surplus hose at the top of the form.

I have also provided means on the attachment whereby a price card, advertisement or the like may be securely supported. This eliminates the necessity of pinning a card to the hose and possibly damaging it, or of merely setting a card on the top of the form and the bunched hose surplus where it may be blown off by drafts.

This invention expedites the application of hose to hosiery forms, does away with any adjustments after the hose is once applied and adds to the appearance of the display. It is economical to produce and the operation of attaching it to the surplus hose and its association with the form require no particular skill.

With the foregoing general objects, features and results in view, as well as certain others which will be apparent from the following explanation, the invention consists of certain novel features in design, construction, mounting and combination of elements, as will be more fully and particularly referred to and specified hereinafter.

Referring to the accompanying drawings:

Fig. 1 is a view in elevation of a hosiery form with a hose displayed thereon and with my attachment in operative position maintaining the hose in stretched condition and supporting a price or advertising card.

Fig. 2 is a view generally similar to Fig. 1 and illustrating the parts of the attachment in separated position.

Fig. 3 is a view in vertical section through the attachment and the upper part of the hosiery form, the remaining parts of which are broken away.

Fig. 4 is a view in vertical section through the top or cover of the attachment when used alone, parts of the hosiery form being broken away.

Fig. 5 is a view taken on line 5-5 of Fig. 3.

In the accompanying drawings I have used the letter F to designate a conventional hosiery form for use as a display device for hosiery. The hosiery form may be made of plastic or any other suitable material and is preferably hollow throughout its length. The form is shaped and may be tinted to simulate the human leg and includes a calf portion 1 and a foot portion 75

3. The form which I have chosen to illustrate in the drawings as one example from among many, simulates a human leg from a point below the knee downwardly, however it is to be distinctly understood that my attachment is operable with forms which may include a knee portion or which may be of reduced length relative to the examples shown in the drawings. It will be recognized that the attachment about to be described has been designed for use on any hosiery form which is of a length such that a surplus portion of hose remains after a hose has been drawn on the form.

At the upper end of the form I provide an annular inwardly extending lip or flange 5 having an inner edge 7 and an outer edge or cover surface 9 where the lip joins with the calf or next adjacent lower portion of the leg. The upper end of the tubular hosiery form is open as at 11. While I have illustrated a hosiery form of hollow or tubular construction throughout the length thereof, it is to be understood that my attachment will function on any hosiery form having a recess at the upper end which is open.

In actual use for the display of hose a tubular hose or stocking 13 of any conventional kind is drawn over the foot 3 of the form and up and over the smooth surface of the calf 1. The hose is pulled up the form until it is tightly stretched thereover, and if the hose has a seam it, of course, is properly positioned to extend up the rear of the form. Since the tubular form F is of substantially less length than the length of the hose; it will be evident that there will be a surplus of hose above the upper end of the form.

The attachment which I have devised includes a spool designated in its entirety by the letter S. This spool includes a central cylindrical axle forming portion 15 connecting an upper circular flange 17 and a lower circular flange 19, which extend radially from the cylindrical portion of the spool. The upper flange 17 is of reduced diameter relative to the lower flange 19 for a purpose to be hereinafter pointed out. A radial slot 21 is formed in the upper flange and extends therethrough from the outer to the inner periphery of the flange. The attachment involved in this application further includes a top or housing member for the spool generally indicated by the letter T which in operative position is adapted to be associated with the spool S and the form in such manner that the hose will be maintained in stretched position on the hosiery form.

The housing T comprises a substantially circular disc like cover member 22 of a diameter greater than the diameter of opening 11 in the form as defined by the inner periphery 7 of lip 5 so that the housing or top may rest on the lip when in operative spool associated position as clearly illustrated in Fig. 3 of the drawings. The cover member 22 is formed with a hemispherical projection forming a handle or knob 23 for facilitating the manipulation of housing T. A slot 25 is provided in the knob 23 for removably supporting a price or advertising card 27 therein. An annular flange 29 depends from the under side of cover 22 at a position thereon inwardly spaced from the periphery of the cover. The depth or width of the depending flange 29 is greater than the axial dimension of the cylindrical portion 15 of the spool. The outer circumferential surface of flange 29 is of downwardly tapering form so that the upper portion

30 thereof is of greater thickness than the lower portion of the flange.

My attachment for a hosiery display form consists of the spool and the housing or top which form a unit when the two elements are operatively associated together in hose storing and anchoring position. The attachment is preferably though not necessarily formed of a relatively light plastic material and may be transparent, translucent or opaque, and of course may be of any desirable color.

After a hose has been drawn on the form and tightly stretched and properly positioned thereon with the upper surplus extending beyond the upper end of the form, the surplus hose, which is of tubular construction, is brought together at a position above and centrally positioned relative to the opening 11 in the form, and the spool S is then brought into position with the greater diameter flange 19 in lower position adjacent to but spaced from the form. The surplus hose is then drawn upwardly through the cylindrical portion 15 of the spool as illustrated at 31. It is desirable in associating the spool with the surplus hose to leave a length A of the hose free of the spool, for this length A forms what I term the tensioning length of surplus and the function thereof will be explained hereinafter. The position of the spool relative to the form in order to provide the tensioning length of surplus hose is clearly illustrated in Fig. 2 of the drawings. The surplus hose is then drawn over the upper edge of the cylinder and then downwardly through the slot 21 in upper flange 17 as at 33 and the remaining surplus is then wound around the cylindrical portion 15 between the upper and lower flanges as shown at 35. When the surplus hose has been anchored to and disposed and stored within the spool as described the spool is positioned within the housing T. The depending flange 29 fits snugly about the periphery of spool flange 19 as clearly illustrated in Fig. 3 of the drawings. It will be appreciated that the spool and its contained surplus hose are housed completely within member T. With the housing and spool associated as described providing a housing and anchoring unit for the surplus hose, the unit is disposed into the form through the opening 11 therein and is pressed into the form until cover or disc 22 of housing T seats on the lip 5 of the form.

When the unit is pressed into operative position within the open end of the form with the cover 22 seated on lip 5 a wedging action occurs between the upper thickened portion of flange 29 and the inner periphery 7 of lip 5 with the hose between the lip and the flange. Flange 29 is thickened at its upper portion sufficiently to create this wedging action and it will be recognized that the unit will be maintained in fully inserted operative position within the form. When the unit is in this operative position the surplus hose A constituting the tensioning length of surplus is drawn and stretched over edge or corners 9 and 7 of lip 5 and across the edge of flange 29 as well as being stretched under tension over flange 19 of the spool. Thus, it will be appreciated that the attachment unit when forced into the form engages the tensioning length A at a plurality of points, pulling the length A into the form to thereby stretch the hose over the display form in tight fashion. The unit also functions in operative position to maintain the length A in stretched position under 75

tension due to the wedging of the flange 29 of the housing into the opening defined by lip 5, with the hose between the inner edge 7 of the lip and the flange. The frictions created at the corners or edges 9 and 7 and where the hose is stretched across the edge of flange 29 and the junction point of flange 19 and cylinder 15 will serve to assist the unit in maintaining length A in stretched condition.

10 It will be evident that the full insertion of the unit into the form causes length A to pull and stretch and thus to tightly pull the hose upwardly on the form into stretched condition thereon. This action occurs since the surplus hose is not only stored within the spool but is also anchored thereto. When the spool and housing are operatively associated the spool to which the surplus hose is anchored is fixed against movement relative to the housing and since the housing is fixed to the form the spool cannot move and hence the point of anchorage of the surplus hose is fixed. Therefor when the unit is in this inserted position the tension on the surplus hose will pull the hose up on the form instead of forcing the surplus hose into the form off the spool. It will be observed that the surplus hose where it extends over cylindrical portion 15 as at 33 is engaged and pressed or clamped by cover disc 22, hence any stretching of the surplus will not go beyond this point 33 and the effective stretching action will occur in the hose on the form as it is tightly pulled up thereon as the unit is inserted in the form.

35 Therefor when the housing and spool are assembled into an operative unit and associated with the surplus hose and inserted into the form the hose on the form will be so tightly stretched thereon that puckering or loosening cannot take place, and due to the wedged association of the unit with the form, the hose therebetween, the 40 hose cannot become loosened and the display will require no attention whatsoever. As long, therefore, as the unit is inserted in operative position in the form the hose will be maintained in stretched condition on the form providing a neat and realistic simulation of a human leg clothed in a stocking.

When the unit is inserted in operative position into the open end 11 of the form the slot 25 in knot 23 is adapted to receive a card 27 therein. The card will be maintained in upright position clearly visible to observers of the hosiery form display. The card may of course have any type of information thereon which it is desired that the observer read. It will be understood that whether or not a card is inserted in the slot in the knob has no effect on the neat and pleasing appearance of the unit.

From the above description it will be apparent that I have devised a hosiery form attachment which will hold a hose in proper stretched position on the form throughout the period of use, and which may be quickly and easily operatively associated with the surplus hose in such a way that it not only serves to maintain the hose in stretched condition but also stores or houses the surplus hose. The attachment also presents a neat and attractive appearance.

In Fig. 4 of the drawings I have illustrated the use of the housing T without the spool S for maintaining a hose in desired condition on a form. When the top or housing T is used without the spool the surplus hose is wound around into a knot 37 and placed into the form through the open end 11. The housing T is then fully

inserted into the opening 11 in the form so that the above described wedging action occurs to maintain the housing in inserted operative position. The tensioning length B is stretched and the stocking on the form is tightly stretched thereover. I have used the same reference characters as those used in describing Figs. 1, 2, 3 and 5 to designate similar parts in the structure illustrated in Fig. 4 of the drawings.

The hosiery forms may be made of a clear or transparent material as well as of opaque materials, and it will be evident that the attachment of this invention which rolls up and houses or stores the surplus hose will prevent a clouding or disturbing appearance within the upper open end of the form as is the case where the surplus hose is merely stuffed into the open end of a transparent form. It is desirable to use an opaque unit or attachment with transparent forms so that the surplus hose within the unit is not visible, and a neat and attractive arrangement is visible through the hosiery form adjacent the upper end thereof.

I claim:

1. A hosiery display form attachment for insertion in the open end of a display form, comprising in combination, a hose attaching member formed for the releasable securing thereto of a part of the surplus extending from a hose on the display form at the open end thereof and being also constructed to provide a storage space therewithin for receiving a part of the surplus hose secured to said member, said hose attaching member having a width less than the diameter of the end opening in the display form and being adapted to be inserted in the end opening and to be suspended in position therein by the hose, a cover member having a flange therearound adapted to fit down over and receive therewithin said attaching member, and said cover member being adapted to be mounted on the form at the open end thereof with said flange inserted into the form in position surrounding said attaching member with the latter suspended in position within the form.

2. A hosiery display form attachment for insertion in the open end of a display form, comprising in combination, a hose attaching member formed to provide an annular open side space therein and therearound for receiving a part of the surplus extending from a hose on the display form in position wound around and secured to said member, said attaching member having a width less than the diameter of the end opening in the display form and being adapted to be inserted in the end opening and to be suspended by the hose in position in the display form drawing the hose into the form under the action of gravity, a cover member having a flange therearound of an external diameter to form a friction fit with the portion of the display form surrounding the end opening, and said cover member being adapted to be mounted on the display form over the open end thereof with said flange inserted through the open end of the form in position engaged with the hose and fitted down over and enclosing said attaching member within the form.

3. A hosiery display form attachment for insertion in the open end of a display form for anchoring a hose on the form, comprising in combination, a hose attaching member formed for the releasable securing thereto of a part of the surplus extending from a hose on the display form at the open end thereof, said attaching

member having a width less than the diameter of the end opening in the display form and being adapted to be inserted in the end opening in position suspended therein by the hose secured thereto, a cover member having a closed top and depending annular flange therearound of an external diameter to form a friction fit with the portion of the display form around the end opening thereof, said cover member flange increasing in thickness from the lower, free edge thereof to said top of the cover member to provide an outer, inwardly inclined wedging surface around the flange, and said cover member being adapted to be mounted on the display form at the open end thereof with said flange being extended through the end opening in wedging engagement with the portion of the display form around said opening, said flange having an internal diameter to fit down over and enclose said attaching member in assembled position thereof on a display form.

4. A hosiery display form attachment for insertion in the open end of a display form, comprising a hose attaching and anchoring member having a central opening therethrough and being formed to provide an open side storage space therearound, said member having a maximum external diameter less than the internal diameter of the open end of a display form, and said member being adapted to be inserted in the open end of a display form with the surplus part of a hose on the form at open end being extended upwardly through said central opening and being wound around said member stored in said open side storage space.

5. A hosiery display form attachment for insertion in the open end of a display form, comprising a hose attaching and anchoring member of a spool-like form having a tubular central body portion and axially spaced, radially extended flanges therearound providing a storage space therebetween open through and around the periphery of the member, the maximum external diameter of said flanges being less than the internal diameter of the open end of a display form, and said attaching member being adapted to be inserted in the open end of a display form in position suspended therein solely by a hose on the form with the surplus part of the hose being extended upwardly through said tubular body portion and secured in position wound around the member confined within the space between said flanges.

6. A hosiery display form attachment for insertion in the open end of a display form, comprising a hose attaching and anchoring member of spool-like form having a tubular central body portion and axially spaced, radially extended upper and lower flanges therearound providing an annular storage space therebetween open through and around the periphery of the member, the maximum external diameter of said flanges being less than the internal diameter of the open end of a display form, the upper of said flanges being formed with a radially disposed slot therethrough, and said attaching member being adapted to be inserted in the open end of a display form in position suspended by a hose on the form with the surplus part of the hose being extended upwardly through said tubular body portion and downwardly through said radial slot in said upper flange and secured in position wound around the member housed within the space between said flanges.

7. A hosiery display form attachment for in-

sertion in the open end of a display form, comprising a hose attaching and anchoring member having a central opening therethrough and being formed to provide an annular storage space therearound opening through the periphery of said member, said member being also formed with a radially disposed slot therethrough at the upper side thereof extending from said central opening across and opening therethrough into said annular space, said member having a maximum external diameter less than the internal diameter of the open end of a display form, and said attaching member being adapted to be inserted in the open end of a display form with the surplus part of a hose on the form at the open end thereof being extended upwardly through said central opening, downwardly through said radial slot and wound around said member within said annular space.

8. A hosiery display form attachment for insertion in the open end of a display form for anchoring a hose on the form, comprising in combination, a hose attaching member of spool-like form having a tubular central body portion and axially spaced upper and lower radially extended flanges therearound providing an annular storage space therebetween open through and around the outer side of said body member, the maximum external diameter of said flange being less than the internal diameter of the open end of a display form, said attaching member being

adapted to be inserted in the open end of a display form in position suspended therein by a hose with the surplus part of the hose being extended upwardly through said tubular body portion and secured in position wound around said member housed within the annular space between said flanges, a cover member having a closed top and a depending annular flange therearound of an external diameter to form a friction fit with the portion of the display form surrounding the end opening thereof and of an internal diameter to fit down over and receive said attaching member therewithin, and said cover member being adapted to be mounted on the form at the open end thereof with said flange inserted into the form in position surrounding and enclosing said attaching member when the latter is in position suspended by the hose within the form.
